(57) **CLAIM**

The ornamental design for a bicycle, as shown and described.

DESCRIPTION

FIG. 1 is a top, front and left side perspective view of a bicycle showing my new design;

FIG. 2 is a bottom, rear and right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detail view of area 9 in FIG. 1;

FIG. 10 is an enlarged detail view of area 10 in FIG. 3; and,

FIG. 11 is an enlarged detail view of area 11 in FIG. 5.

The broken lines in the drawings illustrate the portions of the bicycle, which form no part of the claimed design.

The broken lines encircling the enlarged views and any corresponding leader lines are for annotative purposes only and form no part of the claimed design.

1 Claim, 11 Drawing Sheets
